FROHMAN ANDERSON, OF DETROIT, MICHIGAN

TOY

Application filed October 24, 1929. Serial No. 402,209.

This invention relates to toys, and particularly to that class of toys in which a walking movement is produced, the principal object being the provision of new and novel means for producing this walking movement.

Another object is to provide a toy representing a walking animal, bird or other walking figure, in which a rise and fall, or a hopping movement of the figure occurs during the horizontal movement thereof.

Another object is to provide a toy of the class described having a novel leg construction imparting a rise and fall to the toy during movement in a horizontal direction.

Another object is to provide a toy of the class described having a rotating leg member provided with three legs.

Another object is to provide a toy of the class described having a rotating leg member including three equally spaced legs and so constructed that during movement not more than two legs will be visible at one time.

Another object is to provide a toy of the class described in which each of the leg members is provided with a foot for contact with the floor or other surface and through which the toy is supported from the floor, the bottom of the foot being so formed as to impart to the toy during horizontal movement a simultaneous up and down movement.

Another object is to provide a toy of the class described in which the pulling force necessary to move the toy along the floor remains substantially constant during the elevating movement of the toy relative to the floor.

Another object is to provide a toy of the class described in which the angle between a line passing through the pivotal point of the leg member and the point of contact of the leg member with the floor, and a vertical line passing through the pivotal point of the leg member, remains substantially constant during movement of the toy.

Another object is to provide a toy of the

class described in which the feet are so shaped that the plane of the floor is at all times tangent thereto when in contact therewith.

A further object is to provide a toy of the class described incorporating certain novel features of construction that will be specifically pointed out in the following specification, or that will be obvious therein.

The above being among the objects of the present invention, the same consists in certain novel features of construction and combinations of parts to be hereinafter described with reference to the accompanying drawings, and then claimed, having the above and other objects in view.

In the accompanying drawings which illustrate a suitable embodiment of the present invention, and in which like numerals refer to like parts throughout the several different views,

Fig. 1 is a side elevation of my toy, showing it in full lines in one position of its movement and in dotted lines in another position of its movement.

Fig. 2 is a fragmentary side elevation of my toy shown in another position of its movement.

Fig. 3 is a fragmentary vertical sectional view taken as on the line 3-3 of Fig. 2.

Figs. 4, 5 and 6 are side views of the leg member of my toy showing the same in various states of rotation in order to illustrate the motion imparted to the toy thereby.

Referring to the drawings, and particularly to Figs. 1 and 2, I show a toy comprising a main body portion 10 and a rotating leg member 11 pivoted to the main body portion 10 by a pin such as 12. The main body portion is shown in the drawings as representing a monkey, it being understood that this is merely for the purpose of illustration and that in practice this portion of the device may be formed to represent any type of animal, bird or other creature normally provided with legs by nature for the purpose of walking.

The main body portion 10 is preferably made up of two side members 13 (see Fig. 3) suitably spaced from each other, as shown, in order to provide clearance for the leg member 11 which rotates therebetween. For the purpose of economy in manufacture, the side members 13 are preferably made up from flat stock as shown, although it will be understood that the particular shape and formation of these side members are unimportant as far as the present invention is concerned. The leg member 11 is also preferably made up of flat stock, as indicated in Fig. 3, for the purpose of economy.

As shown best in Figs. 4 to 6, inclusive, the leg member 11 is provided with three equally angularly spaced legs or leg portions 14 and each leg 14 is provided with a foot or foot portion 15. The toy is, of course, supported from the floor through the leg 14 and feet 15. The soles of the feet 15 contact each in their turn with the floor. As illustrated best in Fig. 5, the soles of the feet are so curved in relation to the pivotal point of the foot member that the heel of each foot is closer radially to the pivotal point of the leg member than is the toe of the foot, and the toe and the heel are preferably connected through a smooth curve representing the sole of the foot. The toe and heel of each foot, as viewed in side elevation, preferably merge into the sole of the foot in a smooth and well-rounded curve.

The result of the above described construction will be obvious and is clearly shown in the drawings. Referring to Figs. 1 and 4, the toy is shown in the one position in which two feet are simultaneously in contact with the floor. Inasmuch as the sole of the forward foot at a point adjacent its heel is in contact with the floor, and inasmuch as the forward foot in such a position carries the greater proportion of the weight of the toy, and further, as it is closer to the pivotal center of the leg member than is the toe of the rear foot, it will be obvious that when the leg member is in this position of rotation the toy itself assumes its lowest position with respect to the floor. If, now, the toy is moved forwardly, and assuming that there is sufficient friction between the forward foot, as represented in Figs. 1 and 4, and the floor to prevent slipping of such foot, the leg member 11 will soon assume the position indicated in Fig. 5. In this position, due to the curvature of the bottom of the foot in contact with the floor, it will be apparent that the pivotal axis of the leg member will have moved upwardly with respect to the floor from the position indicated in Figs. 1 and 4. Upon continued movement of the toy and consequent continued rotation of the leg member, it will be apparent that the position of the pivotal point of the leg member will continue to rise relative to the floor until the toe of the foot comes in contact with the floor, as

indicated in dotted lines in Fig. 1, and as closely approached in Fig. 6. The extreme variation in the vertical position of the body member imparted by this movement of the foot member is illustrated at 16 in Fig. 1, and the path of movement of the pivotal point of the foot member with respect to the floor and consequently the path of movement of the body member is represented by the dotted line 17 in Fig. 6. It will thus be apparent that when the toy is moved along the floor the friction between the floor and the leg member will cause rotation of the leg member and consequent rise and fall of the figure, which will impart to the figure that natural rise and fall common to walking movement.

While not essential to the broader aspects of the present invention, I prefer to so shape the body member 10 that only two of the legs 14 will at any time be visible in side elevation, as this imparts a more realistic effect to the toy. The body member 10 shown is shaped to achieve this result.

Also, in the broader aspects of the present invention, the particular curvature of the sole of the foot is not of prime importance so long as it is so shaped with the heel of the foot radially closer to the pivotal point of the leg member than the toe of the foot, so as to impart to the pivotal point and therefore the body of the toy a rising and falling motion during rotation of the leg member. However, in accordance with a further object of the present invention, I prefer that the curvature of the sole of the foot bear a predetermined relation with respect to the pivotal point of the leg member. Specifically, I prefer to form the sole of the feet as a part of a spiral having its center coincident with the pivotal point of the leg member. In such a case the line drawn through the point of contact of the foot with the floor and through the pivotal point of the leg member (indicated in Figs. 4, 5 and 6 as the line 18-18' and 18'' respectively) will at all times remain at a constant angle with respect to a vertical line drawn through the pivotal point of the leg member, such vertical line being indicated as at 19, and the respective angles in each case being indicated as at A-A' and A'' respectively, these angles in such a case all being equal. The reason for this is twofold. First, because by maintaining such angle constant throughout the rotation of the leg member, the force necessary to turn the leg member against gravity acting on the body member will be substantially constant while the sole of any foot 15 is in contact with the floor and thus during elevation of the body member. Further, because of the small angle "a" which it is possible to maintain with this curve of the foot in a three-legged member, it is possible to insure operation of the toy on surfaces affording a minimum of friction with the foot.

This acts to permit operation of the toy on a surface where a minimum of friction exists between the feet and the floor, for in such case the sliding tendency which must be over-
 5 come by friction between the foot and the floor remains substantially constant and un-
 varying and such sliding tendency is main-
 tained at a minimum figure. Another rea-
 son for shaping the feet as above described
 10 is illustrated in Fig. 4. This figure illustrates
 the condition in which two of the feet are si-
 multaneously in contact with the floor. This
 is the position which the leg member will as-
 15 sume ordinarily when the toy is at rest, both
 legs sustaining a part of the weight of the
 toy. By shaping the feet as described, the
 point of contact of the forward leg or foot
 20 with the floor with respect to the vertical
 line 19, which indicates the direction of the
 force of gravity acting on the body of the
 toy, will be considerably less than the dis-
 tance of the point of contact of the rearward
 25 foot 15 with the line 19. These respective
 distances are represented in Fig. 4 as at 20
 and 21 respectively. The result of this con-
 struction is that substantially all of the
 weight is carried on the forward foot, and
 30 thus relatively little effort is required to lift
 the rearward foot 15 when rotation is again
 started, thus insuring rotation of the foot
 upon horizontal movement of the toy with a
 minimum of tendency of the foot to slide rel-
 ative to the floor.

The result of the foregoing construction
 35 is that this formation of the leg member 11
 and curvature of the soles of the feet 15 ins-
 sures a toy of this type which has a hopping
 action during its walking movement, which
 40 will operate on a substantially smooth floor
 affording very little friction between the floor
 and the feet of the toy, and will require a
 minimum of effort to operate it.

Although not essential in all cases, it is
 45 preferable to provide some means connected
 with the toy for imparting movement to it.
 This means may comprise a handle member
 which may be formed as a tail 25 as shown, or
 in any other suitable manner. It is also de-
 50 sirable to provide some means for maintain-
 ing the toy in the proper relative position
 with respect to the floor. One means of ac-
 complishing this is shown in the drawings as
 comprising a cart-like object having a body
 55 portion 26, wheels 27 and a handle portion
 28 which is preferably rigidly connected to
 the body of the toy, as shown. A string 29
 may be attached to the cart 26 for pulling
 the same, if desired, or the cart may be
 60 equipped with any suitable type of motive
 power to turn the wheels 27. The cart may,
 of course, be placed either in front or back
 of the toy.

Formal changes may be made in the spe-
 65 cific embodiment of the invention described
 without departing from the spirit and sub-

stance of the broad invention, the scope of
 which is commensurate with the appended
 claims.

What I claim is:

1. In a device of the type described, in
 combination, a main body member, a leg mem-
 ber pivotally secured thereto, said leg mem-
 ber being provided with a plurality of angu-
 larly arranged legs thereon, each of said legs
 being provided with a foot, the sole of each
 70 of said feet being curved, and the sole of each
 of said feet adjacent the corresponding heel
 being closer radially to the pivotal point of
 said leg member than the sole of said foot
 adjacent the toe thereof, and substantially
 75 all points on said soles adapted for engage-
 ment with a supporting surface.

2. In a toy of the class described, in com-
 bination, a body member and a leg member
 rotatably secured thereto, said leg member
 80 having a plurality of leg portions angularly
 arranged thereon, and each of said leg por-
 tions terminating in a foot, the sole of each
 of said feet being of relatively extended
 length and varying in distance from one end
 85 to the other from the axis of rotation of said
 leg member whereby to cause a continuous
 change in elevation of said body member rela-
 tive to the surface on which said toy is sup-
 ported during contact of said soles with said
 90 surface and movement of said toy thereon.

3. In a toy of the class described, in com-
 bination, a body member and a leg member
 rotatably secured thereto, said leg member
 100 having a plurality of leg portions angularly
 arranged thereon, and each of said leg por-
 tions terminating in a foot, the sole of each
 of said feet being formed as a part of an ap-
 proximately spiral path the center of which
 105 is approximately coincident with the center
 of rotation of said leg member.

4. In a toy of the class described, in com-
 bination, a body member and a leg member ro-
 tatably secured thereto, said leg member hav-
 ing a plurality of leg portions angularly ar-
 ranged thereon, and each of said leg portions
 110 terminating in a foot, the sole of said foot be-
 ing formed as part of a spiral path having its
 center coincident with the axis of rotation of
 said leg member.

5. In a toy of the class described, in com-
 bination, a body member and a leg member
 rotatably secured thereto, said leg member
 having a plurality of leg portions angularly
 arranged thereon, and each of said leg por-
 120 tions terminating in a foot, the soles of said
 feet being formed to maintain a substantial-
 ly constant angle between a vertical line pass-
 ing through the axis of rotation of said leg
 member and a line joining said axis with the
 125 point of contact of said soles with the surface
 on which said toy is supported, during move-
 ment of said soles on said surface.

6. In a toy of the class described adapted
 to be moved along a surface on which it is
 130

- supported, in combination, a body member and a leg member rotatably secured thereto, said leg member being provided with a plurality of equally angularly arranged leg members each of which terminates in a foot arranged to contact with the supporting surface, the soles of said feet being so curved relative to each other that at those points in the operation of said toy where two of said feet are simultaneously in contact with said surface, the distance from the point of intersection with said surface of a vertical line passing through the axis of rotation of said leg member to the point of contact of the forward of said contacting leg members with said surface is less than the distance from said line to the point of contact of the rearward of said contacting leg members with said surface.
- 20 7. In a toy of the class described, a body member, and a supporting member rotatably secured to said body member, said supporting member being provided with a supporting surface formed as part of a spiral, the center 25 of which is substantially coincident with the line of pivot of said supporting member.
8. In a toy or the like, in combination, a main member, and a plurality of rigidly interconnected members adapted to support said main member from a floor or the like, said supporting members being pivoted relative to said main member and being provided with a supporting surface adapted for rolling contact with said floor, each successive increment of length of each said supporting surface, in a direction opposite to the normal direction of rotation of said supporting member, increasing in radial distance from the line of pivot of said supporting member, over the major portion of the length of said surface.
9. In a toy or the like, in combination, a main member, and a plurality of rigidly interconnected members adapted to support said main member from a floor or the like, said supporting members being pivoted relative to said main member and being provided with a supporting surface adapted for rolling contact with said floor, each successive increment of length of each said supporting surface, in a direction opposite to the normal direction of rotation of said supporting member, increasing in radial distance from the line of pivot of said supporting member, over the entire length of said surface.
10. In a toy or the like, in combination, a main member, and a leg member mounted for pivotal movement relative thereto, a plurality of leg portions on said leg member for equal rotation therewith each having a foot, the sole of each of said feet adapted for contact with a floor or the like over substantially its entire length, and the radial distance of the successive increments in the length of each of said soles continuously varying in

radial distance from said line of pivot over substantially the entire length thereof.

11. In a toy or the like, in combination, a main member, and means for supporting said main member from a floor or the like comprising a second member pivotally mounted relative to the first mentioned member and having a plurality of relatively fixed supporting surfaces adapted for contact with said floor and each formed as an approximate spiral approximately axially concentric with said line of pivot.

FROHMAN ANDERSON.
